UNITED STATES PATENT OFFICE.

ROSA C. SMITH, OF MILWAUKEE, WISCONSIN.

TYPE HANGER.

Application filed June 4, 1926. Serial No. 113,783.

This invention relates to improvements in type hangers.

Multigraphing type is put up in standard tubes each containing a plurality of like letters of the alphabet, like numerals or like signs and the tubes have, by custom, been promiscuously placed in boxes which practice has led to considerable waste of time by multigraphing type setters finding the type desired.

It is therefore the object of this invention to provide type hangers which may be placed in a convenient position for multigraphing type setters and upon which the standard tubes containing multigraphing type may be hung systematically according to alphabet, numerals or signs.

It is also an object of this invention to provide for the hanger a movable guard for preventing the accidental removal of the tubes when the type supported by the hanger are not in use.

In the drawings:

Fig. 1 is a side elevation of an embodiment of the type hanger showing tubes suspended therefrom.

Fig. 2 is an end elevation with portions shown in section.

Fig. 3 is a longitudinal section of a standard tube for multigraphing type.

Fig. 4 is an end view of the device shown in Fig. 3.

Fig. 5 is a fragmentary top plan view of a modified form of type hanger.

Fig. 6 is a sectional view taken on the line 6-6 of Fig. 5.

Like parts are identified by the same reference characters throughout the several views.

As shown in Figs. 3 and 4 the standard tube 1 which carries the multigraphing type (not shown) comprises a metal sheet bent to form two arcuate portions 2 and 3 connected by a concave portion 4 and spaced at 5 to provide a slot longitudinally of the tube. The central portion 4 is struck out at each end to form inturned tongues 6 and 7. These tongues retain the type 9 (see Fig. 2) within the tube, such type being

slotted at 10 upon each side as shown in Fig. 2 to receive the margins 11 and 12 of the tube. No invention is claimed in these tubes, but are described merely to indicate their structure as received by a multigraph user. When the tube 1 is hung upon the type hanger disclosed herein, one of the

tongues 6 and 7 is removed to provide an unobstructed slot 13 at one end of such tube.

The type hanger disclosed herein comprises a board 14 having eye screws 15 adapted to receive hooks 16 secured to a wall or other object 17. Upon the face of the board is secured a plurality of hook rods 18 disposed horizontally of such board. Each of these hook rods 18 is designated either by a sign 19, a letter 20 of the alphabet or a numeral 21.

When one of the tongues 6 or 7 has been removed the tube 1 may be hung on the hook rod 18 by inserting the end of such hook through slot 13 in such tube and passing the body of the hook between the margins of slot 5 in the tube. A plurality of tubes may be hung upon each hook and as will be understood, each tube will contain a plurality of similar characters. Thus those tubes containing the same characters will be hung upon a hook designated by a like character.

While I have shown but one embodiment of this invention, it is to be understood that I do not confine myself to this one form as other forms may obviously be made without departing from the spirit of this invention.

Upon the board 14 may also be placed a card or plate 22 with the name of the particular class of type found upon such hanger. Other hangers may be used for other particular classes of type.

In the modified form shown in Figs. 5 and 6 the hanger proper is similar to that shown in Figs. 1 and 2 but is provided with a guard 25 U-shaped in plan and having its ends 26 each pivotally connected by a bolt 27 to a bracket 28 secured to the board 14. Each end 26 of the guard 25 is provided with a stop portion 29 which co-acts with a corresponding bracket 28 supports the guard in a horizontal position as shown in Fig. 6. Above the stop portion 29 the guard is provided with a curved surface 30 to permit the guard to be moved about its pivot to the vertical position shown in dotted lines in Fig. 6. In the horizontal position of the guard its relation to the rods 18 is such that tubes supported by the latter will be prevented from accidentally slipping from the rods when the hanger is being transported or otherwise handled. However, when the guard 25 is moved to the vertical position shown in Fig. 6 the rods 18 are unguarded and a type setter

may freely remove the tubes desired from the rods.

It is preferred that the ends 26 of the guard 25 be engaged frictionally with the brackets 28 to thereby offer some resistance to pivotal movement of the guard. This frictional engagement may be obtained by reason of the resiliency of the ends 26 or by any other well known frictional arrangements.

I claim:

1. The combination with a supporting member, of a plurality of rods supported by said member in spaced relation to each other and each designated by a single character, said characters being arranged in sequence, and tubes each having a slot at one end receiving one of said rods, said tubes each containing a plurality of like character type individually removable from said tubes, the rods supporting said tubes each being designated by a character similar to the character type in the tube supported by said rod.

2. A hanger for type and comprising a supporting member having a plurality of spaced rods secured thereto and a guard hingedly connected to the support for registry with the rods, whereby tubes containing type may be hung upon said rods and be prevented from accidental removal therefrom.

3. In a device of the character described, the combination with a support, of a plurality of rods supported in spaced relation by said support and each disposed in a substantially horizontal plane, brackets on said support, and a guard hingedly connected with said brackets for movement to a posi-

tion in front of said rods, whereby tubes containing type may be supported from said rods and prevented from accidental removal therefrom.

4. In a device of the character described, the combination with a support, of a plurality of rods supported in spaced relation by said support and each disposed in a substantially horizontal plane, a guard pivotally connected to said support for movement vertically above said pivot, and a stop for limiting the movement of said guard to a position in front of said rods.

5. In a device of the character described, the combination with a support, of a plurality of rods supported in spaced relation by said support and each disposed in a substantially horizontal plane, brackets on said support, and a guard hingedly connected with said brackets for movement from a substantially horizontal plane to a substantially vertical plane, said guard being provided with a stop engageable with said bracket to limit the downward movement of said guard to said horizontal plane.

6. In a device of the character described, the combination with a support, of a plurality of rods supported in spaced relation by said support and each disposed in a substantially horizontal plane, brackets on said support, a guard pivotally connected to and frictionally engaged with said brackets, said guard being movable about said pivot from a substantially horizontal plane to a substantially vertical plane, and a stop for supporting said guard in said horizontal plane.

ROSA C. SMITH.
